UNITED STATES PATENT OFFICE

2,173,707

SQUARE SOCKET SCREW WITH SIDE SLOTS

Frank K. Brown, South Dartmouth, Mass., assignor to Continental Screw Company, Bedford, Mass., a corporation of Massachusetts

Application November 27, 1937, Serial No. 176,885

1 Claim. (Cl. 85—45)

My present invention is an improved screw structure and is directed to an improvement in the head, wherein both a square socket for cooperation with a socket wrench, and a plurality of slots opening from said socket on the respective sides for cooperation with a common screwdriver, are provided.

My present invention is an improvement on the combined socket and slotted screw structure 10 of my prior Patent No. 2,082,748, dated June 1, 1937, wherein I have described, illustrated, and claimed a particular form of socket and slot screw structure. In my said prior patent I have shown a form of square or rectangular socket 15 with a plurality of rectangular slots opening from the corners of the socket, and all being formed by a heading or swaging operation, with the periphery of the head of the screw unbroken, the slots terminating short of the periphery of 20 the screw head.

In my present improved form I utilize a square socket with substantially vertical side walls, as shown in my said prior patent, and provide the diametrically opposite pairs of rectangular slots 25 opening from the socket from each side wall and extending toward the periphery of the screw head to constitute the screwdriver-engaging slots.

In my said prior patent the construction as 30 therein shown in preferred form illustrated rectangular slots opening from each corner of the socket. This prior construction thereby shortened the side walls when engaged by a straight socket wrench and also necessitated somewhat 35 short slots because the distance from the corners of the socket to the periphery were limited.

In my present invention wherein I form the rectangular slots directly from the center of the side wall, I am enabled to maintain the socket 40 with the corners intact for better engagement and turning when a socket wrench is used and, furthermore, am enabled to use the rectangular slots of considerably greater length than in the form in my said patent. Thus the available distance between the square side walls of the socket 45 and the periphery of the screw head affords the greatest length possible to be found in the metal of the screw head between the socket and the periphery and, hence, by forming the common screwdriver-receiving slots at this point, I produce a screw head with greater contact of metal 50 in the slots for the common screwdriver, as well as a better socket wrench contact because of the corners being square and uncut.

55 It will be appreciated that the strain and

tension between a driving implement and a screw socket or slot of any kind is greatest at the extreme point of contact between the driving element and the screw, and my present construction utilizes the advantage of this principle.

While my present invention permits the use either of a socket wrench or a common screwdriver, it also facilitates the use of a screwdriving implement combining both the socket wrench features and one or more pairs of wings, such 10 for example as shown in my copending application Ser. No. 172,611, filed Nov. 3, 1937, wherein I have illustrated and claimed a special screwdriver constituting a combined socket and screwdriver, constructed and arranged either for the 15 form shown in my said prior patent or the form of socket and slot screw head herein illustrated.

Referring to the drawing,

Fig. 1 is a plan view of a screw head embodying my present invention of a square socket recess in the head together with a plurality of rectangular openings extending toward the periphery from the center of each side wall;

Fig. 2 is a cross-sectional view on the line 2—2 of Fig. 1;

Fig. 3 is a cross-sectional view on the line 3—3 of Fig. 1;

Fig. 4 is a perspective view;

Fig. 5 is a view illustrating my present improved screw head with a socket wrench for the 30 screwdriver;

Fig. 6 illustrates same with a combined socket and four-winged type of screwdriver, and

Fig. 7 illustrates my present invention with a combined socket and two-winged type of screw- 25 driver.

Referring to the drawing, 1 illustrates the top of the head of the screw with the usual bevelled portion 2 between the head and the threaded shank 3, which shank may be threaded for a 40 "wood" screw, bolt, nut, or any other desired threaded arrangement. Formed in the head 1 is a central rectangular recess 5 being here shown as square, with four side walls 6, 7, 8, and 9 extending downwardly into the head of the screw 45 and with rectangular recesses or openings extending from the center of each of said side walls toward the periphery of the head. These rectangular recesses are designated as 16, 17, 18, and 19 opening respectively from the side walls 50 6, 7, 8, and 9.

Referring to Fig. 5 illustrating my present socket and slot screw head arranged for cooperation with a socket wrench 20, having square or rectangular faces adapted to engage, contact 55

with, and operate the screw head, the socket wrench is inserted in the recess 5, and it will be appreciated that each corner 21 of the socket wrench 20 will engage adjacent side walls of the recess 5 within the corresponding corner recesses 22-22 in the socket 5. Thus a full leverage is obtained between the wrench 20 and the side walls and corners of the socket 5.

Referring to the form shown in Fig. 6, I have illustrated a combined socket and wing type of wrench 25 having the square socket portion 26 and a plurality of side wings 27 adapted to engage the rectangular recesses 16, 17, 18, and 19 in any position in which they may be in alignment when the wrench is fitted into the screw head.

In Fig. 7 I have illustrated a still further modified form of wrench 30 having a square socket portion 31 and a single pair of oppositely positioned wings 32-32 which are adapted to engage any opposite pair of the rectangular slot openings 16 to 19 inclusive in the screw head.

It will, of course, be also appreciated that a common screwdriver may be utilized which would span the central recess 5 and engage an opposite pair of rectangular recesses 16 and 18, or 17 and 19 but I prefer to utilize one of the special types of screwdrivers as illustrated, combining both the socket wrench feature and the winged features, which screwdriver invention is claimed

broadly in my said copending application Ser. No. 172,611 filed Nov. 3, 1937.

The winged members 27 of the type of screwdriver shown at 25 or the wings 32 designated at 30 are preferably bevelled, substantially as shown in the drawing, so as to fit the usual beveling of the rectangular slots and, furthermore, this construction permits a screwdriver to fit and engage screw heads of different sizes within a considerable range, the central socket recess 5 being substantially of standard size while the length of the rectangular slots 16 to 19 is somewhat proportional to the diameter of the head of the screw, as will be readily appreciated.

I claim:

A screw having a head formed with its periphery unbroken, containing therein a central square socket recess formed in the head with substantially perpendicular side walls, and extending axially of the screw a depth substantially equal to the extent of the head, four slots opening from said socket each slot positioned centrally of each side of said squared socket, each slot being rectangular in cross-section, the end wall of each slot tapering from the bottom of the squared socket outwardly and upwardly, said slots being in pairs diametrically opposite each other and symmetrically arranged and all slots terminating within the periphery of the screw head.

FRANK K. BROWN. 30
